UNITED STATES PATENT OFFICE.

CHARLES T. WHITE, OF SOUTH BEND, INDIANA.

FAUCET-CO尤PLING.

SPECIFICATION forming part of Letters Patent No. 727,242, dated May 5, 1903.

Application filed July 15, 1902. Serial No. 115,675. (No model.)

To all whom it may concern:

Be it known that I, CHARLES T. WHITE, a citizen of the United States, residing at South Bend, in the county of St. Joseph and State of Indiana, have invented certain new and useful Improvements in Couplings; and I do hereby declare the following to be a full, clear, and exact description of the invention, such as will enable others skilled in the art to 10 which it appertains to make and use the same.

My invention relates to couplings; and its object is to provide one which may be applied to the discharge end of a pipe or faucet, especially adapting the same for connection 15 with a beer-bottle machine, in which the leakage caused by back pressure is obviated; and with these and other objects in view the invention consists of a casing containing a yielding cone, which is supported therein in 20 such a way as to provide a liquid-tight joint, which automatically seals itself when back pressure is brought to bear thereon, the parts being so aggregated as to insure a rapid and convenient coupling and provide an inexpensive and durable structure.

The invention is illustrated in the accompanying drawings, in which—

Figure 1 is a vertical section of the coupling applied to a faucet. Fig. 2 is a top and 30 side elevation of the yielding cone. Fig. 3 is a top plan view of the coupling with the cone removed. Fig. 4 is a side elevation of the same.

Referring to the drawings, the casing A is 35 composed of a metallic shell having a vertical annular upper wall a, provided on opposite sides thereof with upstanding ears a², adapted to carry the means for attachment to a pipe or faucet. This vertical wall a merges 40 from its lower end into a conical concavo-convex wall a³, which terminates at the contracted pipe extension a⁴.

The cone B may be made of rubber or other yielding material provided with a central 45 downwardly-tapering bore b, in which the end of a discharge pipe or faucet F is inserted, as illustrated in Fig. 1. The upper portion 50 of the cone is thickened, and in its vertical periphery, which corresponds with the vertical wall a of the casing, is formed an annular groove b', adapted to engage the annular rib b² on the casing, by means of which the

cone is supported therein. From the edge of this groove b' the periphery of the cone is curved inwardly and downwardly, as at c, 55 forming a contracted lower end b³ and providing a thin and consequently very resilient lip b⁴, which will seal against the lower face of the rib b² when back pressure is brought to bear thereon and prevent leakage. When 60 the coupling is attached, as in Fig. 1, the lower contracted end b³ is expanded, accentuating the curvature of the periphery c and forming an elongated annular chamber c', the open lower end of which is narrower than 65 the central portion, whereby the back pressure on the surface c has a tendency to cause the bore b and the lip b⁴ to impinge all the tighter against the faucet F and the rib b², respectively, and provide an automatic back- 70 pressure liquid-tight joint.

The ears a² carry any suitable fastening means, which preferably consist of thumb-screws D, the threaded shanks of which pass through the apertures in the ears and terminate in forked extensions d, which engage the discharge end of the faucet F and hold the coupling thereto.

Having thus described my invention, what I claim, and desire to secure by Letters Patent, is—

1. In a coupling, the combination of a non-elastic casing having an elastic packing 85 posited therein, provided with means to detachably secure it to the casing, said packing having a contracted depending free end adapted to form a chamber between the casing and packing, and means on the packing to seal the same against its securing means.

2. In a coupling, the combination with a 90 non-elastic casing having an elastic packing posited therein, said packing having a contracted depending free end and a lip merging from the side thereof, the contracted free end adapted to seal against the pipe and the 95 lip adapted to seal against the casing when back pressure is brought to bear on the packing.

3. In a coupling, the combination of a shell 100 or casing having an upper vertical wall provided with a rib and a contracted lower wall, a yielding cone having a thickened upper portion provided with a groove to engage the rib and a lower contracted portion adapted

to be expanded when attached to a pipe, a lip beneath the groove adapted to seat against the rib when back pressure is brought on the cone, and fastening devices on the casing to engage the pipe.

4. A coupling comprising a casing having a vertical upper wall provided with an annular internal rib and a lower concavo-convex contracted wall, an elastic cone having a thickened upper end provided with an annular groove to engage the rib and a contracted depending thinner end having an inwardly

and downwardly curved periphery providing a chamber between the concavo wall of the casing and the periphery of the depending end, whereby the cone will tightly impinge against the pipe and the rib when back pressure is brought upon the same.

In testimony whereof I affix my signature in presence of two witnesses.

CHARLES T. WHITE.
